MAURICE LEBLANC, OF VAL-SUR-SEINE PAR CROISSY, FRANCE, ASSIGNOR TO SOCIETE ANONYME POUR L'EXPLOITATION DES PROCEDES WESTINGHOUSE LEBLANC, OF PARIS, FRANCE.

STEAM-EJECTOR APPARATUS.

Application filed July 31, 1918. Serial No. 247,651.

To all whom it may concern:

Be it known that I, MAURICE LEBLANC, citizen of the Republic of France, residing at Val-sur-Seine par Croissy, Seine and Oise, France, have invented new and useful Improvements in or Relating to Steam-Ejector Apparatus, of which the following is a specification.

This invention relates to steam ejector apparatus of the kind in which steam ejectors operate in series with intermediate condensers for the production of a vacuum. One well known arrangement of this kind comprises two or more ejectors located parallel to one another with a condenser interposed between the discharge of each ejector and the suction of the next in such a manner that any one ejector has only to draw in the incondensable gases issuing from the preceding ejector.

Such an arrangement necessitates a very complicated pipe system, and an extent of floor space which is not always available, particularly in installations on board ship.

In order to reduce the floor space it is desirable to arrange the ejectors in line with one another and to attach to this group a condenser of elongated form with its axis parallel with that of the ejectors. This arrangement of the apparatus in one group also facilitates the regulation and control of the apparatus.

Up to the present, however, it has not been possible to employ this arrangement exactly as described, owing to the necessity of interposing the intermediate condenser between two successive ejectors.

In principle, a steam ejector comprises the nozzles for the live steam which open into a diffuser of the converging-diverging type in which the withdrawal and compression of the fluid to be extracted from the condenser is effected by the live steam. Up to the present it has not appeared possible to construct ejectors other than with a diffuser having its axis rectilinear and parallel to the general direction of the current of steam, which necessitated placing the intermediate condenser in the prolonged axis of the same line; hence the inconvenience indicated above.

The present invention has for its object an ejector having a diffuser the axis of which forms a curved line, circular or para-

bolic for example, so as to permit the fluid withdrawn to pass out of the ejector in an oblique direction or even perpendicular to the direction of the steam as it leaves the nozzles, that is to say, on its entry into the diffuser.

This ejector is combined with a main condenser an intermediate condenser and a second ejector in such a manner that the first ejector, which forms the suction for the main condenser, is directly connected to the intermediate condenser by its curved diffuser without interposing special connecting piping and the second ejector, which forms the suction for the intermediate condenser, is placed axially in line with the first ejector, the intermediate condenser preferably having an elongated form with its axis parallel and immediately adjacent to those of the ejectors.

The arrangement thus forms a compact unit easy to control and occupying a minimum floor space.

The single figure of the accompanying drawing shows diagrammatically such an arrangement from which the advantages and special features will be readily perceived.

In this figure the first ejector is indicated at *a*, the second in the same axial line at *a'*. The intermediate condenser *b* is located parallel thereto a very short distance away. The suction of the main ejector takes place at *c* the steam entering at *d*. The mixture is withdrawn from the first ejector by the conduit *e*, traverses the auxiliary condenser *b* in which the steam from the first ejector is condensed, the uncondensed air and gases are withdrawn through the conduit *f* by the steam admitted at *g* to the second ejector. The discharge takes place at *h*.

It will be observed that this arrangement greatly simplifies the pipe connections which comprise only short conduits.

Having thus described my invention, what I claim is—

1. In combination with a main condenser a steam ejector provided with a diffuser the axis of which is a curved line so arranged as to permit the fluid withdrawn to be discharged from the ejector in an oblique direction, an auxiliary condenser of elongated form having its axis parallel and immediately adjacent to that of the ejector, and directly connected to the said diffuser,

a second ejector forming the suction from the auxiliary condenser and located in the same axial line as the first ejector, with the object of providing a compact unit easy to control and occupying a minimum floor space.

2. An ejector apparatus comprising a multi-stage ejector, in combination with an interstage cooler, characterized by the fact that the separate stages of the ejector are axially aligned, the axis of the condenser is offset from, but parallel to, the axis of the multi-stage ejector, and the initial stage of the ejector is provided with a curved diffuser which is directly connected to the condenser and the inlet port thereof.

3. An ejector apparatus comprising a multi-stage ejector in combination with a jet condenser communicating with the discharge of one stage and with the inlet of another stage of the ejector, characterized by that the separate stages are axially aligned, are secured together as a unit, the axis of the condenser is offset from, but parallel to, the axis of the multi-stage ejec-

tor, and one stage of the ejector is provided with a curved diffuser secured to the condenser and discharging directly into the inlet port thereof.

4. An ejector apparatus comprising a multi-stage ejector in combination with an intermediate condenser of elongated form, characterized by that the successive stages of the multi-stage ejector are so arranged that their rectilinear axes are in the same straight line parallel with the axis of the elongated condenser and the initial stage of the ejector is provided with a curved diffuser discharging into the condenser and the suction of the next successive stage communicates directly with the condenser so as to form an apparatus of minimum width.

In testimony whereof I have signed my name to this specification in the presence of two subscribing witnesses.

MAURICE LEBLANC.
